COMBINED CAN OPENER AND KNIFE SHARPENER

Alfred W. Madl, Mequon, Wis., assignor to John Oster
Manufacturing Co., Milwaukee, Wis., a corporation of
Wisconsin

Filed Apr. 4, 1963, Ser. No. 74,304

Term of patent 14 years

(Cl. D37—1)

FIG. 1 is a front elevational view of a combined can opener and knife sharpener embodying my design;

FIG. 2 is a right side elevational view thereof;

FIG. 3 is a top plan view thereof;

FIG. 4 is a left side elevational view thereof;

FIG. 5 is a rear elevational view thereof; and

FIG. 6 is a fragmentary sectional view taken along line 6-6 of FIG. 5.

I claim:

The ornamental design for a combined can opener and knife sharpener, as shown.
